UNITED STATES PATENT OFFICE.

AUGUST BECKER, OF BROOKLYN, NEW YORK.

DESIGN FOR A LACE CURTAIN.

42,600.

Specification for Design.

Patented June 11, 1912.

Application filed September 6, 1911. Serial No. 647,967. Term of patent 14 years.

To all whom it may concern:

Be it known that I, AUGUST BECKER, a citizen of the United States, residing at Brooklyn, in the county of Kings and State of New York, have invented a new, original, and ornamental Design for Lace Curtains, of which the following is a specification, reference being had to the accompanying drawing, forming a part thereof.

The figure is a plan view of a lace curtain with a central portion broken away, showing my design.

I claim:

The ornamental design for a lace curtain, as shown.

Signed at New York, in the county of Kings, and State of New York, this 8th day of August, 1911.

AUGUST BECKER.
